GOLF GLOVE

James D. Giambazi, 12 Abbott St.,
Cumberland, R.I. 02864

Filed Jan. 14, 1975, Ser. No. 540,886

Term of patent 14 years

Int. Cl. D2—06

U.S. Cl. D2—361

FIG. 1

FIG. 2

FIG. 3.

FIG. 1 is a perspective view of the back of a golf glove showing my new design;

FIG. 2 is a side perspective view of the design of FIG. 1 with the back flaps in open position; and

FIG. 3 is a perspective view of the front of the golf glove of FIG. 1.

I claim:

The ornamental design for a golf glove, as shown.
